(57) **CLAIM**

The ornamental design for a lamp, as shown and described.

DESCRIPTION

FIG. 1 is a perspective view of a lamp showing a first embodiment of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is a perspective view of a lamp showing a second embodiment of my new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is another perspective view thereof.

The dashed broken lines in the drawings illustrate portions of the lamp which form no part of the claimed design. The dash-dot broken lines shown in FIGS. 1-5 and 7-8 are included for the purpose of illustrating the boundary between the claimed and the unclaimed subject matter that is shown in broken lines. The dash-dot broken lines form no part of the claimed design.
